CAN OPENER

Filed Oct. 9, 1929

FIG. 1.

FIG. 2.

FIG. 3.

FIG. 4.

J. R. COMPTON,
INVENTOR

BY *Victor J. Evans*

ATTORNEY

UNITED STATES PATENT OFFICE

JOHN R. COMPTON, OF VINCENNES, INDIANA

CAN OPENER

Application filed October 9, 1929. Serial No. 398,486.

The present invention contemplates the provision of a can opener of novel construction, and one which normally lies flat on top of the can, and is capable of being extended and manipulated in a manner to quickly and conveniently sever the top of the can as the occasion requires.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views and wherein:

Figure 1 is a fragmentary sectional view through a can showing the invention associated therewith and the normal position of the parts.

Figure 2 is a similar view showing how the can opener is initially extended for use.

Figure 3 is a top plan view of Figure 1.

Figure 4 is a top plan view of Figure 2.

Figure 5 is a perspective view of the cutter section.

Referring to the drawings in detail 10 indicates the body of a can, the cover of which is represented at 11. This cover is preferably formed with a centrally located depression 12 and an additional depression or pocket 13 adjacent the edge thereof.

The present invention contemplates a can opener adapted to be attached to the top of the can so that it will be available when its use is desired, the construction being such that the can opener lies flat upon the top of the can or substantially flush therewith in the normal position of the parts.

The can opener itself includes a section 14 which is of channel-like formation in cross section for the major portion of its length, and preferably tapers toward one end. The inner end of this section is provided with an opening 15 to accommodate a pivot 16, the head of which is received by the depression 12 above referred to. The section 14 is

thus supported on the top of the can for pivotal movement about the latter when its use is desired. The outer end of the section 14 is characterized by a substantially V-shaped cutting blade 17 which is arranged at a right angle to the section and normally positioned in the pocket or depression 13 as clearly illustrated in Figures 1 and 2. Slidably received by the channel-like section 14 is a flat handle 18 which is also tapered longitudinally as illustrated. This handle is partly projected from one end of the section 14 to lie flat upon the top of the can in the normal position of parts as illustrated in Figure 3, but when use of the can opener is desired, the handle is slid through the section 14 to project beyond the other end thereof and beyond the periphery of the can as illustrated in Figure 2. By reason of the fact that the section 14 and the handle 18 are tapered, the handle is wedged within the section 14 and held fixed relatively thereto when extended beyond the periphery of the can for use. It is then only necessary to lift the section 14 upwardly a slight distance to remove the cutting blade 17 from the pocket 13, and subsequently shift the cutting blade to one side of the pocket, whereupon it can be easily forced downwardly to penetrate the top of the can. Then by moving the lever 18 in either direction, the section 14 is moved about its pivot 16 to quickly and conveniently sever the top of the can as will be readily understood.

While it is believed that from the foregoing description, the nature and advantages of the invention will be readily apparent, I desire to have it understood, that I do not limit myself to what is herein shown and described and that such changes may be resorted to when desired as fall within the scope of what is claimed.

What is claimed is:

1. In combination, a can including a top having a centrally located depression, and a depression adjacent the outer edge thereof forming a pocket, an opener comprising a section arranged upon the top of the can and pivoted centrally thereon, with the head of the pivot arranged in said central depression, 100

a cutting blade depending from one end of the section and normally positioned in said pocket, said section being of tapered channel-like formation, a tapered handle slidably fitted in said section and normally lying flat upon the top of the can, whereby the device normally lies within the confines of the top of the can and adapted to be extended beyond the edge of the latter to lift the blade from said pocket, and to move said section about its pivot with the blade penetrating said top.

2. In combination, a can including a top having a centrally located depression, and a depression adjacent the outer edge thereof forming a pocket, an opener comprising a section arranged on the top of the can, a headed pivot element carried by one end of the section, with said head arranged in the depression to permit said section to be moved pivotally about the can, a cutting blade depending from one end of the section and normally positioned in said pocket, and cooperating with said headed pivot to hold the section normally fixed to the top of the can, said section being of tapered channel-like formation, a tapered handle slidably fitted in said section and normally lying flat upon the top of the can, within the confines of the latter, and adapted to be extended beyond the edge of the latter to lift the blade from said pocket, and to move said section about its pivot with the blade penetrating said top.

33. In testimony whereof I affix my signature.
JOHN R. COMPTON.
